(57) **CLAIM**

The ornamental design for a salon chair with tilttable back, as shown and described.

DESCRIPTION

FIG. 1 is a perspective view of a salon chair with tilttable back showing my new design;

FIG. 2 is a front elevational view of the salon chair with tilttable back of FIG. 1;

FIG. 3 is a top plan view of the salon chair with tilttable back of FIG. 1;

FIG. 4 is a right side elevational view of the salon chair with tilttable back of FIG. 1;

FIG. 5 is a left side elevational view of the salon chair with tilttable back of FIG. 1;

FIG. 6 is a back elevational view of the salon chair with tilttable back;

FIG. 7 is a bottom plan view of the salon chair with tilttable back of FIG. 1; and,

FIG. 8 is a perspective view of the salon chair with tilttable back of my new design wherein the back is tilted to its inclined position.
